tion

Application January 16, 1941, Serial No. 374,784
In Switzerland March 26, 1940

14 Claims. (Cl. 74—300)

The present invention relates to improvements in tread crank mechanisms, particularly for cycles.

Various arrangements have already been proposed in order to adapt the tread crank mechanism especially of cycles to the conditions and the peculiarity of the legs and their muscular exertion to provide a design of said mechanism in such a manner that the path of the pedals, instead of being a circle, approaches a more linear shape, i. e. a less or more flattened curve, so that the motion of the legs is transformed into an up and downward motion. However, as a consequence of the abrupt inversion of motion at the ends of the curve, the mechanism of this kind resulted in undesirable accelerating and retarding effects, which produced particularly at the ascending pedal a disturbing impact on the sole of the foot of the cyclist, so as to produce fatigue in spite of the higher efficiency much more rapidly. It is to be noted that the human legs are no metallic connecting-rods there is a lack of the rotating mass which is required by every crank mechanism in order to assist by means of the stored up energy in overcoming the dead center positions. Hence it is not sufficient to improve these conditions by mechanical modifications of the crank mechanism, but at the same time this mechanism must be adapted to the peculiarities of the leg motions as set out in the following explanations.

In dividing the leg motion exerted during the drive of the rotating pedals in four sections corresponding to the quadrants I—II, II—III, III—IV and IV—I of the circle C as illustrated in Fig. 1, the vectors being inclined under 45° to the horizontal line, the following phases of motion occur when moving in the direction of the arrow p:

1. The downward phase I—II substantially produces the driving force; 2. The backward phase II—III is for the stroke inversion; 3. The upward phase III—IV not only does not produce any driving force, but produces rather a braking effect, particularly when the cyclist is fatigued; and 4. The forward phase IV—I for the stroke inversion.

It is obvious that in order to obtain a kinematic improvement and particularly an adaptation to the structural organization of the legs which do likewise not perform a circular motion when jumping, the phases I and II must possibly be eliminated and hence the tread motion must take place substantially along the fully shown curve in the direction of the diagonal 50

I—III, which results in the advantage as compared to the circular tread path, that the angle of the knee and the deflexion of the shank of the cyclist becomes considerably reduced from 5 the point I to point III and backwards, and as a consequence thereof there is not only obtained a better efficiency in the mechanical sense, but also a reduction of the extension and compression of the muscles and tendons, which enhance 10 considerably the fatigue as well as the strains in the knee. As a result, the extreme angles of the knee become reduced in value as clearly shown in Fig. 2. In said figure, the dotted lines show the extreme positions of the leg for a circular tread path and the full lines the positions of the leg when the tread path is a curve lying 15 in the direction of the diagonal I—III. Furthermore this figure shows that the angle at the knee remains during the tread motion substantially of a constant value and does not undergo 20 a modification from the stretched position to an excess acute angle in a manner to produce an over-exertion of the tendons of the knee-articulation. Besides, the leg motion is an almost uniform 25 one and the leg organism is not influenced by the successive changes of acceleration and retardation.

As the general direction of motion in this arrangement extends from an upper anterior point to an under posterior point with an inclination of 15-75° to the horizontal, the resulting kind of motion and force effect of the legs is nearly like that exerted when jumping, hence a natural operation, whilst the hitherto used circular path of the pedal treading required a more or less artificial and therefore forced adaptation of the human organs to the mechanism. At the same time, the said arrangement permits also an increase of the effective tread stroke by a 30 prolongation of the tread crank arm, as shown in dotted lines at V—VI in Fig. 1, so as to produce a considerable increase of output without any increase of the angle of the knee deflexion. Of course it is of high importance that as aforementioned the inversion of motion does not occur in the short instant in which the longitudinal axis of the pedal arms are in alignment, but that the configuration of the tread path is such that in said alignment position there results a 35 more or less smooth transition from one direction of motion to the other to which the muscle organism can adapt itself without any force, so as to obtain a perfect synchronism between the mechanical and the human motive organs.

The aforesaid desiderata are realized with the

tread crank mechanisms, according to the invention because both tread cranks are journaled each separately by means of diametrically opposed pivots in a rotor element which is rotatorily supported in a bearing element secured in the cycle frame and correlated to the pivots of the tread cranks by means of transmitting elements in such a way, that the two pivots of the tread cranks when driving the pedals rotate together with said rotor element around its axis of rotation in such a manner that the path of the motion of said pedals forms an ellipse, the greater axis of which is inclined downwardly to the rear.

This connecting means could be realized as a mechanism known under the designation of crank-loop, but preferably a planetary wheel gear will be used, the planet wheels of which meshing with stationary internal teeth rims are rigidly connected with said trunnions of the tread cranks and the wheel support of which forms the rotor element connected with the sprocket wheel, which rotates in this arrangement in backward direction opposed to the tread crank motion. This seems at first sight not to be compatible with the direction of motion of the chain and the back wheel of the cycle, however the said arrangement which differs completely from all conventional designs, can easily be realized in practice in such a manner that the chain is running over a backward leading pulley and then from this with its lower branch over the sprocket wheel of the rear wheel axle in driving mesh. This arrangement offers the further advantage that the rear wheel may be taken off and replaced and effect a tightening of the chain by means of its sprocket wheel, so that the chain can never loosen so much that there is the danger of falling off.

As a further object of the invention means may be provided enabling a variation of the inclination of the great axis of the ellipse forming the path of the pedals in order to adapt the said inclination to the individual requirements of the cyclist as well as to the alteration of country gradients during the drive.

Of course a driving mechanism of the aforesaid arrangement must not be used merely for cycles, but in general for all tread crank mechanisms, as for the drive of fans etc.

Under the designation "ellipse" is to be understood every closed oval curve even if it does not correspond in all its parts to the ellipse equation.

Besides the aforesaid schematical explaining Figures 1 and 2, three preferred embodiments of the object of the invention are illustrated in the accompanying drawings, which show in

Fig. 3 a tread crank mechanism in an elevation view;

Fig. 4 a view in vertical axial section and

Fig. 5 at a smaller scale the arrangement of said mechanism in a cycle;

Fig. 6 shows a view in horizontal section through the central axis of the tread bearing axle, of another embodiment of the invention, and

Fig. 7 a view in lateral elevation;

Fig. 8 illustrates a further embodiment of the invention, the left half showing a view in elevation and the right half a view in vertical section through the central axis of the tread bearing axle;

Fig. 9 shows a view in lateral elevation and

Fig. 10 at a smaller scale the arrangement of the said mechanism in a cycle.

Referring now to the drawings in which like characters of reference designate similar parts in the various views, the tread crank mechanism according to the first embodiment illustrated in Figs. 3-5 comprises a wheel shaped bearing element 1 rigidly secured in the cycle frame, the frame tubes R1 and R2 (Fig. 5) as well as the lower fork of the cycle frame being fastened to the outer rim of said bearing element 1. In the hub of the bearing element 1 is journaled by means of ball bearings 2 and a fit bushing 3 the rotor element 4 composed of two halves. The two halves 4a and 4b of said rotor element are centred by means of dowel pins 6 and fastened together by means of screw bolts 5 with nuts. The rotor element 4 constitutes a planet wheel support and is provided with two diametrically opposed trunnions 7 on which are journaled by means of ball bearings 8 the planet wheels 9. Each of said planet wheels 9 is meshing with an internally toothed gear rim 10. The two gear rims 10 are situated on both sides of the bearing element 1 in which their collars 10c are inserted with running fit. For assembling the two gear rims 10, they are provided with pairwise arranged angled brackets 15 welded or otherwise secured to the rims, and between each pair of brackets 15 is arranged a screw bolt 18, surrounded by a spacing bushing 16. The spacing bushing 16 passes through a slot in the bearing element 1, such as to permit a motion of the gear rims in a circumferential direction. The exterior portions 4b and 4d of the rotor element which are fastened together by screw bolts 12 with the interior portions 4a and 4c respectively, constitute together with the rings 13 fitted into the gear rims 10 lateral closures, so that the whole constitutes a closed housing which can be filled with lubricating grease. Into the rings 13 are inserted sealing rings 14 which slide on the circumference of the portions 4b and 4d. In bosses of the rotor portions 4b and 4d are inserted ball bearings 11 in which are journaled the trunnions 9c of the tread cranks T, the arms of which are secured in a well known manner by means of screw bolts S on the trunnions which are fastened centrally to the planet wheels 9. Furthermore, to the right hand portion 4d of the rotor is secured the sprocket wheel 17 by means of internally protruding arms 17a and screws 17s, so as to rotate together with the rotor.

In Fig. 3 the path of motion of the tread cranks 55 T, i. e. the pedals P, is shown as being an ellipse A. The long axis a of the ellipse A is shown as being vertical for the sake of fitting on the drawings, but really the arrangement in the bicycle itself is such that the long axis a of the ellipse, which is in line with the tread cranks at their aligned position, is inclined at an angle α to the horizontal as shown on Fig. 5. In the present case this angle is 53 degrees approximately. In order to accommodate the position of the axis a and of the crank position to the necessities of the cyclist on the one hand and to the slope of the road on the other hand, the following device is provided for:

To each gear rim 10 a toothed segment 19 (Figs. 3 and 4) is fixed to the exterior surface by means of the screws 19s. With these toothed segments 19 mesh pinions 20, keyed on a common shaft 21 journaled in a support 22, free to rotate thereon, and which support is fixed to the outer surface of the bearing disk 1. On the

shaft 21 a bevel-wheel is also keyed, meshing with its mate 24, fixed on the lower end of a shaft 25. This shaft 25 is arranged inside the frame tube R2 (Fig. 5) and extends up to the front fork V. Another pair of bevel-wheels is arranged, similar to gears 23—24, which pair can be rotated by means of a lever 26. An oscillating motion of the lever is transmitted through the upper pair of bevel-wheels, the shaft 25, the pair of bevel-wheels 23—24, the shaft 21 and the pinions 20 and finally to the toothed segments 19, so that the gear rims 10 can be rotated, whereby the position of the axis *a* is varied accordingly. This graduation preferably ranges within 15 and 75 degrees or within narrower limits.

At the rear end of the lower frame fork G a leading pulley 28 is supported on the stud 29 for guiding the chain 27, which runs over the driving sprocket wheel 17. From the leading pulley 28 the lower branch of chain runs over the sprocket wheel 31 keyed on the axle of the rear wheel H. This axle is bedded in a downwards inclined open slot 30s of the fork head 30, so as to automatically tighten the chain on placing the rear wheel.

The mode of operation of the described tread crank mechanism is as follows:

On treading the cranks T in the direction of the arrow (Fig. 3) the planet wheels 9 revolve in the same direction rolling on the gear rims 10 at a rate of one in two. Since the latter are fixed to the frame, the rotor element 4 revolves, but in opposite direction, i. e. backward as shown by the arrow.

From these two motions results the elliptical path A for the pedals P which path at the ends of the long axle *a* allows a smooth passing, free of jerks, and for the rest this elliptical path increases the effective power stroke whereas the amplitude of the angle of the shank, i. e. of the knee, limited by the short axis of the elliptic path, is by far smaller than in the case of pure circular motion.

In the case of the second embodiment of the invention shown in Figs. 6 and 7, a circular supporting element 31, is fixed to the frame of cycle, similar to the arrangement as described above. In the hub 31n of this supporting element a tread bearing axle 34 is journalled on radial ball bearings 32 and 33, such as to be secured against axial displacement. The ends of this axle are fitted with diametrically opposed cranks 35, secured by screw wedges 36 against rotary displacement. These cranks 35, laterally cranked toward the central plane, together with the tread bearing axle 34 represent the rotor element. In the widened outer end portion of each crank 35 the tread crank pin 38 is journalled on the ball-bearings 37, the projecting outer portion of this pin being fitted with the tread crank T in the usual way. To the inner end of each tread crank pin a sprocket wheel 39 is fleyed and in alignment with it another sprocket wheel 40 of twice as many teeth is fixed to the hub of the supporting element 1. These two sprocket wheels 39—40 of each pair are coupled by means of a sprocket chain 41 as an intermediate member. The supporting element 31 at each side is closed by means of covers 42 and 43, fixed to the rotor. The driving sprocket wheel 17 is fixed to projections 35a and 35b of the crank 35 on the side of the sprocket wheel by means of three arms 17a.

The arrangement on the bicycle is similar to

that of the first described example with the long axis of the pedal path inclined downward to the rear and the mode of operation is also the same since in this case equally the rotor is revolving backwardly and the upper branch of the chain runs astern on account of rolling the intermediate chains 41 on the fixed sprocket wheels 40, so that the tread crank pins are compelled to revolve on the tread bearing axle.

10 In the third embodiment of the invention as shown in Figs. 8, 9 and 10, the fixed supporting element is represented by a cylindrical bushing 51, welded into the cycle frame. Inside this bushing, the revolving tread bearing axle 54 is 15 journalled in the ball bearings 52. On both projecting outer ends of the tread bearing axle 54 are fixed cranks 55 similar to those of the above described design and fixed to the axle 54 by means of screw wedges 56. In this case the rotor element 20 is built up of these axles and cranks. The outer and widened ends of the cranks 55, offset laterally toward the central plane, are fitted with ball bearings 57 in which are journalled the pins 58 of pinions 59, and the projecting outer ends of these pins are fitted with the tread cranks T. In alignment with these pinions 59 the projecting side ends of the bearing bushing 51 are fitted with the gear rim 60 of a diameter twice that of the outer pinions, i. e. of the planet wheels 59. Each pair of wheels 59—60 is fitted with an intermediate member, as a pinion 61, the pin 61' of which is journalled in the crank 55 and held in position by means of the screw 62. The sprocket wheel 17 is fixed to projecting arms 55a and 55b of the crank 55 at the side of the sprocket wheel by means of three arms 17a and screws 17s. The gear wheels 59, 60 and 61 are enclosed in a casing 63 of two sections, one of which is fixed to the crank by means of the screw 64 (at left hand of Fig. 8 this case is not shown for the sake of clearness and for the same reason on Fig. 9 both casings are shown but by chain lines).

Fig. 10 shows the arrangement of the mechanism on the bicycle with the long axis of the elliptical pedal path A inclined downwardly to the rear at an angle of approximately 20°. The upper taut branch of the chain 27 runs over two vertically superposed leading pulleys 28 and 28', arranged on a projection 29' of the rear frame fork, on to the driven sprocket wheel 31, over 90° of its circumference. For the rest the arrangement and mode of operation is similar as in the aforescribed embodiments. Instead of but one intermediate member a plurality can be provided for, in which case the arrangement could be such that the sprocket wheel with the rotor would not revolve astern but ahead.

With the arrangement of the tread crank mechanism according to this invention, it is possible to give the position of the two tread cranks a different angle and the cranks themselves a different length in order to adjust the mechanism to the differences of the two legs in the case of a cyclist having legs of different length, i. e. a crippled leg or foot, which means a great help to such cyclists on travelling and which improves their security, whereas hitherto in such cases the cyclist could not but tread on one crank only, the other crank being fixed to the bearing of the tread crank, pointing downward.

With the last described arrangement the outer diameter of the tread bearing is not larger than that of the tread bearing as used hitherto. I do not limit my invention to the structures

shown and described, as modifications, within the scope of the appended claims may be made without departing from the spirit of my invention.

Having thus described my invention, what I claim as new and desire to secure by Letters Patent is:

1. In a tread crank mechanism, particularly for cycles, the combination comprising a bearing element mounted in the cycle frame, a rotor element rotatively mounted in said bearing element, a pair of opposed journals located in said rotor element, a tread crank having a shaft located in each of said journals, a planetary member fixed to each shaft, transmitting means interposed between each planetary member and said rotor element and a sprocket wheel fixed to said rotor element for driving the cycle whereby upon rotation of said tread cranks and rotor element the pedals upon said tread cranks will describe an elliptical path having the major axis thereof inclined downwardly and rearwardly.

2. In a tread crank mechanism, particularly for cycles, the combination comprising a bearing element mounted in the cycle frame, a rotor element rotatively mounted in said bearing element, a pair of opposed journals located in said rotor element, a tread crank having a shaft located in each of said journals, a planetary member fixed to each shaft, a pair of fixed internal gears cooperating with said planetary members, a sprocket wheel fixed to said rotor element and means cooperating with said sprocket wheel for driving the cycle.

3. In a tread crank mechanism, particularly for cycles, the combination comprising a bearing element mounted in the cycle frame, a rotor element rotatively mounted in said bearing element, a pair of opposed journals located in said rotor element, a tread crank having a shaft located in each of said journals, a planetary member fixed to each shaft, a pair of fixed internal gears cooperating with said planetary members, a sprocket wheel fixed to said rotor element, means cooperating with said sprocket wheel for driving the cycle, said rotor element comprising two portions journalled in the hub of said bearing element, means securing said portions together and each of said portions comprising an outer disc, a ring tightly contacting the adjacent internal gear and a packing ring associated with said first mentioned ring forming a side closure so that a closed casing is formed.

4. In a tread crank mechanism, particularly for cycles, the combination comprising a bearing element mounted in the cycle frame, a rotor element rotatively mounted in said bearing element, a pair of opposed journals located in said rotor element, a tread crank having a shaft located in each of said journals, a planetary member fixed to each shaft, a pair of fixed internal gears cooperating with said planetary members, a sprocket wheel fixed to said rotor element, means cooperating with said sprocket wheel for driving the cycle, said rotor element comprising two portions journalled in the hub of said bearing element, means securing said portions together and each of said portions comprising an outer disc, a ring tightly contacting the adjacent internal gear, a packing ring associated with said first mentioned ring forming a side closure so that a closed casing is formed

and said sprocket wheel being fixed to one of said outer discs.

5. In a tread crank mechanism, particularly for cycles, the combination comprising a bearing element mounted in the cycle frame, a rotor element rotatively mounted in said bearing element, a pair of opposed journals located in said rotor element, a tread crank having a shaft located in each of said journals, a planetary member fixed to each shaft, a pair of rotatively adjustable internal gears cooperating with said planetary members, a sprocket wheel fixed to said rotor element and means cooperating with said sprocket wheel for driving the cycle.

10 6. In a tread crank mechanism, particularly for cycles, the combination comprising a bearing element mounted in the cycle frame, a rotor element rotatively mounted in said bearing element, a pair of opposed journals located in said rotor element, a tread crank having a shaft located in each of said journals, a planetary member fixed to each shaft, a pair of rotatively adjustable internal gears cooperating with said planetary members, a sprocket wheel fixed to said rotor element, means cooperating with said sprocket wheel for driving the cycle and means for securing said adjustable internal gears together.

15 7. In a tread crank mechanism, particularly for cycles, the combination comprising a bearing element mounted in the cycle frame, a rotor element rotatively mounted in said bearing element, a pair of opposed journals located in said rotor element, a tread crank having a shaft located in each of said journals, a planetary member fixed to each shaft, a pair of rotatively adjustable internal gears cooperating with said planetary members, a sprocket wheel fixed to said rotor element, means cooperating with said sprocket wheel for driving the cycle, said adjustable internal gears having toothed segments upon their exterior peripheries, pinions meshing with said segments, a shaft, a pinion upon said shaft for driving said pinions so that upon rotation of said shaft said internal gears may be adjusted with relation to said bearing element whereby the major axis of the path of travel of the pedals may be varied.

20 8. In a tread crank mechanism, particularly for cycles, the combination comprising a bearing element mounted in the cycle frame, a rotor element rotatively mounted in said bearing element, a pair of opposed journals located in said rotor element, a tread crank having a shaft located in each of said journals, a planetary member fixed to each shaft, transmitting means interposed between each planetary member and said rotor element and a sprocket wheel fixed to said rotor element for driving the cycle whereby upon rotation of said tread cranks and rotor element the pedals upon said tread cranks will describe an elliptical path having the major axis thereof inclined downwardly and rearwardly, a second sprocket wheel fixed to the shaft of the driving wheel of said cycle, a sprocket chain cooperating with both of said sprocket wheels, a leading pulley for said chain over which said sprocket chain passes so the lower stretch of said sprocket chain may cooperate with said sprocket wheel upon the shaft of said driving wheel.

25 9. In a tread crank mechanism, particularly for cycles, the combination comprising a bearing element mounted in the cycle frame, a rotor element rotatively mounted in said bearing ele-

ment, a pair of opposed journals located in said rotor element, a tread crank having a pedal having a shaft located in each of said journals, a planetary member fixed to each shaft, transmitting means interposed between each planetary member and said rotor element and a sprocket wheel fixed to said rotor element for driving the cycle whereby upon rotation of said tread cranks and rotor element the pedals upon said tread cranks will describe an elliptical path having the major axis thereof inclined downwardly and rearwardly, said transmitting means comprising coating gears.

10. In a tread crank mechanism, particularly for cycles, the combination comprising a bearing element mounted in the cycle frame, a rotor element rotatively mounted in said bearing element, a pair of opposed journals located in said rotor element, a tread crank having a pedal having a shaft located in each of said journals, a planetary member fixed to each shaft, transmitting means interposed between each planetary member and said rotor element and a sprocket wheel fixed to said rotor element for driving the cycle whereby upon rotation of said tread cranks and rotor element the pedals upon said tread cranks will describe an elliptical path having the major axis thereof inclined downwardly and rearwardly, said transmitting means comprising sprocket wheels fixed to said bearing element and sprocket chains cooperating with said planetary members and said last named sprocket wheels.

11. In a tread crank mechanism, particularly for cycles, the combination comprising a bearing element mounted in the cycle frame, a rotor element rotatively mounted in said bearing element, a pair of opposed journals located in said rotor element, a tread crank having a pedal having a shaft located in each of said journals, a planetary member fixed to each shaft, transmitting means interposed between each planetary member and said rotor element and a sprocket wheel fixed to said rotor element for driving the cycle whereby upon rotation of said tread cranks and rotor element the pedals upon said tread cranks will describe an elliptical path having the major axis thereof inclined downwardly and rearwardly, covers fixed to the tread cranks, cooperating covers fixed to said bearing element and rotating with said rotor element.

12. In a tread crank mechanism, particularly for cycles, the combination comprising a bearing element formed as a cylindrical bushing rigidly fixed in the cycle frame, gears fixed to

said bearing element, a tread bearing axle rotatively journaled in said bearing member, oppositely disposed cranks fixed to said axle, a pair of tread cranks, shafts for said tread cranks 5 rotatively mounted in said first mentioned cranks, means interconnecting said shafts and said gears upon said bearing element, a rotor arm fixed to said axle and having one end rotatively mounted concentric to one of said shafts, a 10 sprocket wheel fixed to said arm and means for driving the cycle cooperating with said sprocket wheel.

13. In a tread crank mechanism, particularly for cycles, the combination comprising a bearing element formed as a cylindrical bushing rigidly fixed in the cycle frame, gears fixed to said bearing element, a tread bearing axle rotatively journaled in said bearing member, oppositely disposed cranks fixed to said axle, a pair of 15 tread cranks, shafts for said tread cranks rotatively mounted in said first mentioned cranks, means interconnecting said shafts and said gears upon said bearing element, a rotor arm fixed to said axle and having one end rotatively mounted concentric to one of said shafts, a sprocket wheel fixed to said arm, means for 20 driving the cycle cooperating with said sprocket wheel, said means interconnecting said shafts and said gears comprising planet wheels upon each shaft having one-half the diameter of said gears and pinions interposed between said planet wheels and said gears, said pinions being journaled on said first mentioned cranks.

14. In a tread crank mechanism, particularly for cycles, the combination comprising a bearing element formed as a cylindrical bushing rigidly fixed in the cycle frame, gears fixed to said bearing element, a tread bearing axle rotatively journaled to said bearing member, oppositely disposed crank fixed to said axle, a pair of 35 tread cranks, shafts for said tread cranks rotatively mounted in said first mentioned cranks, means interconnecting said shafts and said gears upon said bearing element, an arm fixed to said 40 axle and having one end rotatively mounted concentric to one of said shafts, a sprocket wheel fixed to said arm, means for driving the cycle cooperating with said sprocket wheel, said means interconnecting said shafts and said gears comprising planet wheels upon each shaft having one-half the diameter of said gears and pinions interposed between said planet wheels and said gears, said pinions being journaled on said 45 first mentioned cranks and a casing enclosing said planet wheels, pinions and gears.

FRITZ LIENHARD.
